UNITED STATES PATENT OFFICE.

LOUIS BRUDICK, OF RALSTON, PENNSYLVANIA.

ENVELOP-OPENER.

1,267,372.

Specification of Letters Patent.

Patented May 28, 1918.

Application filed March 23, 1918. Serial No. 224,319.

To all whom it may concern:

Be it known that I, LOUIS BRUDICK, a subject of the Emperor of Austria, residing at Ralston, county of Lycoming, and State of Pennsylvania, have invented certain new and useful Improvements in Envelop-Openers, of which the following is a specification.

This invention relates to improvements in envelopes and has as its special object the provision of means whereby an envelop may be opened in a rapid and convenient manner by means carried within itself.

A further object is to provide an envelop which may be used for letters or like inclosures and which is unobjectionable in appearance or use from any view point whatever.

The invention includes the novel arrangement of parts hereinafter described and shown in the accompanying drawing, forming a material part of this disclosure, and in which:—

Figure 1 is a fragmentary perspective view of an envelop, parts being broken away in order to show the opening device as applied thereto.

Fig. 2 is a fragmentary side elevational view of an envelop as it appears before mailing.

Fig. 3 is another side elevational view of an envelop indicating the method used in opening the same.

Fig. 4 is a like side elevational view showing the envelop partially open.

Fig. 5 is a sectional view, looking on line 5—5 of Fig. 2, and

Fig. 6 is a fragmentary side elevational view of the opening device in detail.

The invention may be applied to any ordinary form of commercial envelop, as indicated by the numeral 10, provided with the usual closing lap 11 and adapted to contain inclosures of any desired character whatever.

Secured to one of the lower corners of the envelop between the front 12 and back thereof, is a clip 14, in which is engaged one end of an elastic cord 15, to the outer

free end of which is fastened a hook-like element 18, the inner edge of which is reduced in thickness and fashion in the form of knife blade or cutter so arranged as to normally rest over the folded edge at the end of the envelop, as indicated in Figs. 1 and 2.

In operation, the envelop having been filled with whatever inclosures desired and properly sealed it is in condition to be mailed. When received and at the time it is desired to open the envelop, the extending hook element 18, is grasped by the fingers, as clearly indicated in Fig. 3, and raised upward so as to tension the elastic fibers of the cord 15, whereupon, it being suddenly released, the interior sharpened edge of the element comes in violent contact with the folded edge, severing the same and, due to the elasticity of the cord material, forcing the hook 18 nearly or quite to the end opposite lower corner, closely adjacent to the clip 14, thereby permitting the envelop to be opened without further difficulty.

Having thus described my invention what I claim as new and desire to secure by Letters Patent, is.

1. In an envelop opener, the combination with an envelop, of a clip secured at one of the lower corners thereof between the inner and outer walls, of an elastic cord secured in said clip, said cord extending upward to the opposite corner of the envelop, and a hook having an internal knife edge formed therewith engaged with said elastic cord at its opposite end.

2. In an envelop opener, the combination with an envelop of ordinary commercial type, of an elastic cord secured between the inner and outer walls of said envelop at one of the lower corners thereof, said cord extending through at the opposite upper corner, and a hook shaped cutter element secured to the free end of said elastic cord, said cutter element extending into position to be operated.

3. In an envelop opener, the combination with a commercial envelop, of a clip engaged at one of the lower corners thereof,

an elastic cord secured in said clip, said elastic cord extending closely adjacent to the folded edge of the envelop, a cutter formed in the shape of a hook secured to 5 the free end of said elastic cord, said cutter being adapted to engage with the folded edge opposite to said clip, said cutter being operable whereby said elastic cord, due to its elasticity, causes the folded edge or seam of the envelop to be severed. 10

In testimony whereof I have affixed my signature.

LOUIS BRUDICK.
